UNITED STATES PATENT OFFICE

2,454,699

COMPOSITE CHAIR

Frederic Hirsch, New York, N. Y., assignor, by
mesne assignments, to Astra Bent Wood Furni-
ture Company, New York, N. Y., a partnership

Application February 12, 1945, Serial No. 577,532

5 Claims. (Cl. 155—194)

1

This invention relates to composite chairs, and relates more particularly to chairs made of two or more members that may easily be assembled, and taken apart.

One of the principal objects of the invention is to provide a chair that is light in weight and rigidly constructed and, when taken apart, may be compactly stored and shipped.

Another object is to provide such a chair that may be held together by screws without the same being visible from the outside.

Another object is to provide such a chair that will have great stability.

A further object is to provide such a chair which can be taken apart by the removal of a few screws.

A further object is to provide such a chair that is made of aluminum tubing or the like, which combines rigidity with a degree of elasticity necessary for a comfortable seat.

Further objects and advantages of the invention will be set forth in part in the following specification and in part will be obvious therefrom without being specifically referred to, the same being realized and attained as pointed out in the claims hereof.

Heretofore, chairs of metal tubing have been used, as well as composite chairs. The tubing chairs have mostly been made of an S-shaped construction which provided a very resilient structure without, however, giving great rigidity. These chairs also have used up a large amount of space for storing and shipping.

Composite chairs as known to the prior art very often are complicated to assemble, and also may lack a rigidity such as absolutely required for office chairs or the like. Furthermore, in many cases, these composite chairs do not provide large enough a base necessary for great stability; and an unstable chair does not only cause discomfort, but might involve accidents.

The present invention intends to overcome such shortcomings and provides a composite chair made of metal tubing having a large base and stability, and due to its construction, combines rigidity with a certain degree of elasticity. When the chair is assembled it can take as much punishment as a non-composite chair, yet can be taken apart in a few seconds' time. From the appearance of the assembled chair it cannot be discovered that it may easily be taken apart.

With the above and other objects of the invention in view, the invention consists in the novel construction, arrangement and combination of

2

various devices, elements and parts, as set forth in the claims hereof, certain embodiments of the same being illustrated in the accompanying drawings and described in the specification.

5 In the accompanying drawings,

Fig. 1 is a perspective view of a composite chair incorporating my invention;

Fig. 2 is a perspective view of a chair similar to the one shown in Fig. 1;

Fig. 3 is a sectional view of Fig. 1;

Fig. 4 is a cross section taken along line 4—4 of Fig. 3;

Fig. 5 is a cross section taken along line 5—5 of Fig. 3; and

Fig. 6 is an elevational view showing the parts of several chairs taken apart, in "man-on-man" position for shipping.

In carrying the invention into effect in the embodiments which I have selected for illustration in the accompanying drawings and for description in this specification, I provide:

A pair of substantially symmetrical side pieces 11 and 12, each thereof formed of a single piece of bent aluminum tubing or other suitable tubing material. The side piece 11 is shaped to provide an end portion forming a leg 13, a substantially horizontal portion 16, and a back portion 18, to which correspond an end portion forming a leg 14, a horizontal portion 17 which is substantially perpendicular to the leg 14, and a back portion 19 of the side piece 12. Each portion of said side piece 12 is parallel to the corresponding portion of the side piece 11.

A seat 21 made of wood, or textile, or other suitable rigid or pliable material is fastened to the horizontal portions 16 and 17 which act as seat supports, by means of flat head steel screws 22 which are countersunk into the material of said seat.

40 A back 23, made of wood or other suitable rigid or pliable material, is secured near the upper end to the back portions 18 and 19, of each of said side pieces 11 and 12, by means of flat head steel screws which are countersunk into the material of said back 23.

A connecting piece 24, made of a single piece of bent aluminum tubing or other tubing material, is formed to provide a pair of legs 26 and 27, respectively, a pair of parallel portions 28 and 29, perpendicular to the legs 26 and 27, respectively, and a connecting portion 31 between said parallel portions 28 and 29 and integral therewith.

Said connecting piece or member 24 is detachably secured to the underside of each of said side pieces 11 and 12, as shown in Fig. 1, by fastening

the outside of the intersecting L-shaped bend between the leg 26 and the parallel portion 28 of the member 24 to the underside of the horizontal portion 16 at a point thereof near the back portion 18 of said side piece 11; similarly, the other parallel portion 29 is fastened to the underside of the horizontal portion 17 of said side piece 12 by means of one of the countersunk screws 22 which at the same time secures the seat 21 to its place.

As shown in Fig. 4, the screw 22 reaches through the seat 21 and the horizontal portion 17 into the parallel portion 29 which carries a thread for engaging said screw 22. The member 24 is so secured to the side pieces 11 and 12 that each parallel portion 28 and 29, respectively, forms a small angle with the horizontal portions 16 and 17 of said side pieces. Consequently, the legs 26 and 27 of said member 24 form the same small angle with a vertical line and, therefore, with the legs 13 and 14 of said side pieces 11 and 12. This position of the member with relation to the rest of the chair structure provides a large base for the chair, which assures great stability.

The connecting portion 31 of said connecting piece or member 24 is secured to the vertical legs 13 and 14 of said side pieces at the L-shaped bends intersecting said connecting portion 31 with the parallel portions 28 and 29, respectively. As shown in Fig. 5, the L-shaped bend of the tubing has a hole 32 on the inner wall, sufficiently large to allow the head of a screw 33 to pass, and has a hole 34 coaxial therewith through which the screw 33 protrudes to engage a thread provided in the leg 14. A similar manner of fastening is provided in connection with the leg 13 of the side piece 11. The screws 33 are completely hidden from the outside, and at the same time, can easily be removed by inserting a screw driver through the holes 32 to loosen the screws 33.

The seat, which at its rear end is connected to the horizontal portions 16 and 17 by means of the screws 22 (see Fig. 4), is connected at its forward end to the same horizontal portions by means of additional flat head screws.

Another modification of the present invention is shown in Fig. 2, in which the entire chair structure is provided by two members 24 and 36, respectively. The lower member 24 is substantially like the one shown in Fig. 1. The upper member 36 has two side pieces 37 and 38, conforming to the side pieces 11 and 12 of Fig. 1, which are, however, integrally connected to each other, thereby providing a back 39. A back cover made of wood or other material may be secured thereto if desired, but the same is not shown in the drawings, as the chair may be used without such cover. In all other respects, this modification has the same structure as the chair shown in Fig. 1 and described herein above.

The type of composite chairs described herein has a great rigidity, yet, especially when the seat 21 is made of pliable material, a certain degree of elasticity is provided. The seat 21 may be pliable as it performs no structural function. The connection between the side pieces of either type chair (Fig. 1 or Fig. 2) is provided by the connecting piece or member 24.

When the chair is taken apart, the pieces thereof may be laid "man-on-man" because the connecting piece 24 as well as the side pieces or the member 36, are rectangularly shaped. A considerable saving of space results when the structural parts are placed "man-on-man" as shown in Fig. 6, which saving of space is particu-

larly useful and advantageous for storing and shipping.

I do not limit myself to the particular details of construction set forth in the foregoing specification and illustrated in the accompanying drawings, as the same refer to and set forth only certain embodiments of the invention and it is obvious that the same may be modified, within the scope of the appended claims, without departing from the spirit and scope of the invention.

Having thus described the invention, what I claim as new and desire to be secured by Letters Patent, is as follows:

1. A composite chair, comprising in combination: a member which comprises two seat supporting portions substantially parallel and spaced from each other for a distance and horizontally disposed for providing a seat support, two front legs integrally connected to an end of said seat supporting portions and at right angle therewith, two back portions integrally connected to the other end of said seat supporting portions and at right angle therewith and arranged in an upward direction therefrom, and a back connected to said back portions and extending therebetween; a second member which comprises two portions substantially parallel and spaced from each other for the same distance as said seat supporting portions of said first member and each disposed below a seat supporting portion of said first member and detachably connected with relation to the underside thereof and forming a small angle therewith, two rear legs integrally connected to an end of said two portions and at right angle therewith, and a connecting portion integrally extending between said two portions and connecting the other ends thereof and horizontally disposed below said two seat supporting portions of said first member and spaced therefrom and adjacent said front legs of said first member and detachably connected with relation thereto; and a seat secured to the upper side of said seat supporting portions of said first member.
2. A composite chair, comprising in combination: a member which comprises two seat supporting portions substantially parallel and spaced from each other for a distance and horizontally disposed for providing a seat support, two front legs integrally connected to an end of said seat supporting portions and at right angle therewith, two back portions integrally connected to the other end of said seat supporting portions and at right angle therewith and arranged in an upward direction therefrom, and an integral back extending between said back portions; a second member which comprises two portions substantially parallel and spaced from each other for the same distance as said seat supporting portions of said first member and each disposed below a seat supporting portion of said first member and detachably connected with relation to the underside thereof and forming a small angle therewith, two rear legs integrally connected to an end of said two portions and at right angle therewith, and a connecting portion integrally extending between said two portions and connecting the other ends thereof and horizontally disposed below said two seat supporting portions of said first member and spaced therefrom and adjacent said front legs of said first member and detachably connected with relation thereto; and a seat secured to the upper side of said seat supporting portions of said first member.
3. In a composite chair, two members made

each of a single piece of metal tubing or the like, each member comprising two side pieces bent at right angle and disposed substantially parallel and spaced from each other for a distance common to both members and an integral connection extending therebetween, the side pieces of one of said members composed of two substantially horizontal portions and two vertical portions at one end thereof for providing a seat support and two front legs respectively, the integral connection extending upright between the other ends of said horizontal portions for providing a back, the side pieces of said other member composed of two inclined portions each arranged below a horizontal portion of said first member and detachably connected to the underside thereof and forming a small angle therewith, and two portions perpendicular thereto at one end thereof for providing two rear legs, the integral connection extending between the other ends of said inclined portions of said second member and substantially horizontally disposed below said two horizontal portions of said first member and adjacent said two vertical portions of said first member and detachably connected with relation thereto.

4. A composite chair, comprising in combination: a member which comprises two straight seat supporting portions substantially parallel and spaced from each other for a distance and horizontally disposed for providing a seat support, two front legs integrally connected to an end of said seat supporting portions and at right angle therewith, and an arc shaped back having two opposite ends which are integrally connected to the other end of said seat supporting portions and at right angle therewith and arranged in an upward direction therefrom; a second member which comprises two straight portions substantially parallel and spaced from each other for the same distance as said seat supporting portions of said first member and each disposed below a seat supporting portion of said first member and detachably connected to the underside thereof and forming a small angle therewith, two rear legs integrally connected to an end of said two straight portions and at right angle therewith, and a straight connecting portion integrally extending between said two straight por-

5 tions and connecting the other ends thereof and horizontally disposed below said two seat supporting portions of said first member and spaced therefrom and adjacent the rear of said front legs of said first member and detachably connected with relation thereto; and a seat secured to the upper side of said seat supporting portions of said first member.

6 5. In a composite chair, a substantially vertically disposed arc shaped connecting portion adapted to provide a back, and having two downward pointing opposite ends which are first turned horizontal in substantially parallel relation and spaced for a certain distance arranged to form a seat support and thence turned downwardly for forming front legs, and a connecting portion substantially horizontally disposed below said seat supporting portions and spaced therefrom and adjacent said front legs and detachably secured with relation thereto and having two opposite ends which are first turned perpendicular to said connecting portion and substantially parallel and spaced from each other for a distance equal to said first certain distance and which are disposed below said seat supporting portions and detachably connected to the underside thereof and inclined upwardly for forming a small angle therewith, said ends thence turned downwardly for forming rear legs.
